UNITED STATES PATENT OFFICE

JULIAN S. FRIEDE, OF TEXARKANA, TEXAS

DESIGN FOR A DISPLAY STAND

Application filed April 11, 1932. Serial No. 43,455. Term of patent 3½ years.

To all whom it may concern:

Be it known that I, JULIAN S. FRIEDE, a citizen of the United States, residing at Texarkana, in the county of Bowie and State of Texas, have invented a new, original, and ornamental Design for Display Stand, of which the following is a specification, reference being had to the accompanying drawing, forming part thereof.

The figure is a perspective view of a display stand, showing my new design.

I claim:

The ornamental design for a display stand as shown.

JULIAN S. FRIEDE.
